UNITED STATES PATENT OFFICE.

ELIZABETH WARWICK, OF CHICAGO, ILLINOIS.

ELECTRIC RAILWAY.

SPECIFICATION forming part of Letters Patent No. 638,155, dated November 28, 1899.

Application filed March 18, 1899. Serial No. 709,661. (No model.)

To all whom it may concern:

Be it known that I, ELIZABETH WARWICK, a citizen of the United States, residing at 147 Belden avenue, Chicago, Illinois, have invented certain new and useful Improvements in and Connected with Electric Railways and Tramways, of which the following is a specification.

This invention relates to improvements in and connected with electric railways and tramways, and has reference more particularly to the construction and arrangement of the trolley rail or line conductor.

One object of the improvements is to enable a conductor of sufficient sectional area to carry the whole current for working the line of railway or tramway to be used without of necessity requiring the employment of feed wires or conductors and at the same time keeping the resistance so low that there is practically no waste of energy.

Another object is to enable the conductor to be supported in a very efficient and permanent manner, and at the same time permit of its free expansion and contraction without interfering with the electrical continuity thereof.

In order that the invention may be clearly understood and readily carried into effect, I will proceed to describe the same more fully by aid of the accompanying drawings, in which—

Figure 1 is a longitudinal section; and Fig. 2 a transverse section on the line 1 1 of Fig. 1, showing the means I employ for supporting the conductor applied to a conduit system.

A A are the line conductors, B B the yokes, and C C the slot-rails, between which the trolley-leg on the car projects downwardly to reach the conductors A, as is well understood. Each of the said conductors is preferably made of hard drawn copper and of the cross-sectional shape indicated in the drawings. The said yokes are formed with lateral brackets b b, to each of which is fitted a detachable clamping block or cover b'. Between such bracket and clamping-block is arranged an insulating-block b³, which is horizontally divided into two parts, so as to permit of the

conductor being readily placed in position between them.

b³ b³ are bolts extending through the bracket and clamping-block and serving to tightly clamp the parts together without, however, exerting undue strain thereon. The said insulating-blocks have flanges b⁴, which engage with corresponding recesses in the bracket and cover, so as to prevent the said blocks from shifting laterally. It will be obvious that instead of the insulating-blocks being clamped to the bracket on the yoke they may be clamped to suitable projections or supports specially provided for them in the conduit.

The conductors are in cross-section of tapered or other suitable formation, and the extent to which they protrude from the insulating-blocks is advantageously made sufficient to permit of the trolley-wheel to run against the side or top or bottom surface thereof. I do not, however, confine myself to this specific form of conductor.

What I claim is—

1. In a conduit system of electric railways, the combination of a line conductor, a bracket substantially parallel therewith, a detachable cover, insulating-blocks held between the bracket and cover and recessed to receive the conductor, and means upon opposite sides of the insulating-blocks for securing the bracket, cover, blocks and conductor in position, as set forth.

2. In a conduit system of electric railways, the combination of a yoke, a lateral bracket thereon, having a recess, a cover with a corresponding recess, insulating-blocks with flanges disposed in said recesses, a line conductor held in recesses in said blocks and extended beyond the same, and means passed through the bracket and cover for holding all of said parts together, as set forth.

3. In a conduit system for electric railways, the combination of a yoke provided with lateral bracket having a recess in its upper face, a reversely-arranged cover with similar recess in its under face, insulating-blocks having flanges seated in said recesses and provided with recesses at their outer meeting faces forming an undercut recess to receive the line

conductor, the tapered line conductor seated in said recess, and bolts passed through the cover and bracket independent of the insulating-blocks and serving to hold all of said 5 parts firmly together, substantially as described.

In testimony whereof I have hereunto set

my hand, in presence of two subscribing witnesses this, 7th day of March, 1899.

ELIZABETH WARWICK.
